DELAY FUSE

John C. Gillette, Washington, D. C., and
Braxton H. Tabb, Jr., Arlington, Va.

Application February 15, 1945, Serial No. 577,982

2 Claims. (Cl. 102—74)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to improvements in delay fuses for explosive shells. Its primary object is to provide the fuse that will be safe under all conditions incident to handling and in shipment, such for instance, as the accidental dropping of the shell or its subjection to jars or vibration incident to shipment.

The standard fuse upon which we seek to improve depends solely upon centrifugal force operated devices to hold the firing pin separated from the primer when in unarmed position, but these devices are so arranged that they may be operated by forces other than centrifugal force as by the dropping of the shell or in some other unintended emergency, whereas in the instant invention a positive barrier is interposed between these elements in unarmed position, supplemented by a positive lock removed upon setback, to allow the centrifugal force devices to function to remove the barrier between the firing pin and primer.

The fuse about to be described may be used in the 90 mm. M71 shell employing standard fuse point detonating assembly M48A2, a portion of such assembly being illustrated to show the application of the present invention.

In the drawings illustrating the invention:

Figure 1 is a central section through the fuse, fuse point and nose of a shell, with our improved fuse in position in the fuse body.

Figure 2 is an enlarged central section of the fuse removed from the fuse body, showing the fuse in unarmed position.

Figure 3 is a similar view taken at right angles to Figure 2, with the fuse in unarmed position.

Figure 4 is a sectional plane view taken about on line 4—4 of Figure 2 and.

Figure 5 is a perspective view of the centrifugal slide member of this invention.

Referring to the drawings and particularly Figure 1, the numeral 1 designates the fuse body formed with a reduced threaded portion 2 for threading into the shell. The body is provided with a central flash passage 3, a continuation of which extends through the fuse as will be more particularly pointed out later on. Carried by the forward portion of the fuse body and intersecting the flash passage 3, there is a device known as an interrupter and designated here by the numeral 4.

This device is ordinarily operated by centrifugal force and in connection with the delay fuse

2

in the fuse body but it may be manually locked across the flash passage from the outside of the shell cap to permit the flash from the detonator assembly in the nose 6 from reaching the booster (not shown) which is located in the forward end of the explosive charge in the shell. When the interrupter is set to operate by centrifugal force the detonator assembly is the first to operate upon impact of the shell, but should it fail to do so, the delay fuse in the fuse body will cause the explosion of the shell.

The parts heretofore described form no part of the present invention and as stated at the outset, are only illustrated to show the relation of our improvements to them.

The following relates to our improvement. There is a cylindrical cavity 8 in the fuse body in which fits a cylindrical stationary fuse casing 9 held in the cavity by an externally threaded ring 9' threaded into a rabbet at the end of the cavity, the ring being provided with an annular shoulder 10 against which the rear end of the fuse casing rests. The numeral 11 designates a cylindrical delay plunger body which fits in the casing 9 and is slidable therein. Near the periphery of the body 11 there is a bore 12 in the upper end of which is a primer 13 which may be of any suitable construction. This is adapted to cooperate with the firing pin 14 supported in the front end of the casing 9 in line with the primer. The bore 12 is continued below the primer and is partly occupied by a suitable powder column below which is a short diagonal passage 15 leading to the booster in the explosive charge of the shell as usual. This powder train or column may be conventional and will be of a kind suitable for igniting the booster in the shell.

The plunger body is formed at its upper end with an annular flange 16 to the upper edge of 40 which is attached a disk 17 between which and the front end of the casing is a spiral spring 18 normally urging the plunger body away from the forward end of the casing. The plunger body is further provided with a transverse recess 19 in 45 which is mounted a slide 20 operable by centrifugal force. The slide has a flash passage 21 therethrough which when the fuse is in unarmed position, registers with the flash passage 22 in the plunger body, said passage 22 leading to the booster in the shell charge. The passage 21 registers at its forward end with a hole 23 centrally located in the disk 17, the hole in the disk and the flash passages 21 and 22 completing the avenue through the plunger body to the booster 50 when the delay fuse is in unarmed position. The

slide 20 has a laterally extending lip 24 having a hole 25 therein removed somewhat from its outer edge leaving a solid portion or barrier 26, which when the fuse is unarmed, covers up and protects the primer 13 from the firing pin 14.

The slide is bored from opposite sides to form sockets 27 for the reception of the reduced ends 28 of centrifugal force responsive bolts 29 slidable in the bores 30 in the plunger body 11. The outer ends 31 of the bolts abut disks 32 threaded in the bores 30, there being springs 33 between the disks and bolts urging the inner ends of the bolt into the sockets in the slide. The bolts are reduced in diameter to form annular recesses 34 for the reception of heads 35 of setback bolts 36 slidable in appropriately shaped bores 37 in the plunger body and backed by springs 38 held in the bores by screw plugs 39. It will be seen that as a result of the cooperation with the slide of the centrifugal force responsive bolts 29 and the setback bolts 36, the slide is positively locked against movement when the fuse is in unarmed position and cannot be moved by any force other than centrifugal force to which the bolts respond when the deceleration sets in, beyond the muzzle of the gun.

Carried by the casing 9 is a stop pin 40 opposite the inner end of which is a hole 41 in the disk 17 to permit the passage of the end of the pin when the slide reaches armed position, the relative localities of the hole 23 in the disk, and the flash passage 21 in the slide, being such that when the slide reaches armed position the stop pin will be aligned with the passage 21 through hole 41 and permit the plunger body to move toward the firing pin, the stop providing an additional safety device for the fuse when in unarmed position.

The floor 42 for the slide recess 19 is slightly upwardly and outwardly inclined and the bottom of the slide is correspondingly shaped so that the slide, during the period of acceleration will remain in unarmed position due to the forces of setback and friction between the slide and the bottom of the recess.

During the movement of the slide from unarmed position, shown in Figure 2, to armed position, the slide due to the shape of its bottom and that of the floor of the recess, will rise slightly and to provide for this movement there is left a clearance between the disk 17 and the top of the slide.

The disk 17 has a hole 43 in line with the firing pin 14, through which the pin passes to contact the primer upon impact of the shell, the barrier 26 at this time being removed.

The stop 40 terminates just short of the top of the slide 20 and will engage the slide and limit the forward movement of the delay body, should there be a slight movement of said body toward the end of the casing against spring 18. This engagement between the stop and slide takes place before the firing pin reaches the barrier 26, thus preventing any injury to the firing pin that might result from contact with the barrier in the handling of the shell containing the fuse.

In the unarmed position shown in Figures 2 and 3, the firing pin cannot reach the primer since the slide 20 of which the barrier 26 forms a part, is locked by the centrifugal force responsive bolts 29, and said bolts are in turn locked by setback bolts 36. Upon firing the projectile the setback bolts are withdrawn from the recesses in the bolts 29 permitting said bolts to respond to centrifugal force unlocking the slide, which,

by centrifugal force is moved to the outer end of the recesses 19 to armed position, withdrawing the barrier 26 permitting the firing pin to reach the primer when the delay body 11 moves forwardly upon impact of the shell.

In normal position, stop 40 prevents the whole delay body 11 from moving forward in the casing for any considerable distance, but when the fuse is in armed position, the stop is in position to enter the passage 21 in the slide and thus no longer hinder the movement of the delay body upon impact of the shell.

As heretofore stated, interrupter 4 is not part of the present invention and is shown only to show the relation of the instant fuse to said interrupter. As shown, the interrupter is locked across the flash passage 3 by engagement between the upper end of the interrupter and eccentric shoulder on the lower end of its casing and in position to prevent functioning of the super-quick fuses. Rotation of the casing from the position shown will unlock the interrupter and permit it to respond to centrifugal force thereby permitting the super-quick element to function.

From the foregoing it will be seen that a safe and simple fuse is provided, which, while operable by centrifugal force, those devices so operated are so safeguarded that it is impossible to operate the fuse by accident or in the ordinary handling of the shell in which the fuse is contained, because the firing pin cannot reach the primer until the barrier 26 is removed from its path, the slide of which the barrier is a part, cannot move unless the centrifugal force operated bolts 29 are withdrawn, and these bolts cannot move until the setback bolts 36 are withdrawn by setback, which withdrawal is only effected when the shell is fired.

We claim:

1. In a delay fuse for a shell, a fuse body, a stationary delay fuse casing in said body, a plunger slidable in said casing; an eccentrically located bore in said plunger establishing communication between the plunger and the explosive charge in a shell, a primer in said bore, a firing pin carried by the casing in line with the primer and adapted to contact said primer upon the forward movement of the plunger upon impact, a transverse recess in the plunger, a slide in said recess responsive to centrifugal force, said slide being provided with a laterally extending lip normally covering the primer to prevent accidental engagement between the primer and firing pin, centrifugal force responsive bolts in the plunger in engagement with the slide to normally lock it against movement, setback means engaging the bolts and operable to release the slide upon the firing of the shell to render the primer available to the firing pin upon impact of the shell.

2. In a delay fuse for shells, a fuse body, a stationary fuse-casing in said body, a delay plunger slidable in said casing, firing means actuated upon impact of the shell, yielding means between the plunger and the casing urging the plunger to the rear of the casing, a slide transversely movable in said plunger and responsive to centrifugal force, said slide having a recess therein and a portion normally blocking the firing means, a projection carried by the casing and adapted to prevent operative movement of the delay plunger when the fuse is in unarmed position, said projection being positioned to register with and be received in said recess in the slide, when the fuse

is in armed position to allow the plunger to reach armed position prior to impact of the shell.
